UNITED STATES PATENT OFFICE.

JOSEPH BARRAJA-FRAUENFELDER, OF BRIDGEPORT, CONNECTICUT, ASSIGNOR TO THE LAKE TORPEDO BOAT COMPANY OF MAINE, OF BRIDGEPORT, CONNECTICUT, A CORPORATION OF MAINE.

HYDROPLANE-OPERATING MECHANISM FOR SUBMARINE BOATS.

1,330,754.

Specification of Letters Patent.

Patented Feb. 10, 1920.

Application filed April 14, 1917. Serial No. 162,024.

To all whom it may concern:

Be it known that I, JOSEPH BARRAJA-FRAUENFELDER, a citizen of the United States, residing at Bridgeport, in the county 5 of Fairfield and State of Connecticut, have invented certain new and useful Improvements in Hydroplane-Operating Mechanism for Submarine Boats, of which the following is a specification.

10 The invention relates to submarine boats, and more particularly to hydroplane operating mechanism for controlling the submerging and rising of the boat and maintaining it on an even keel, and has for its 15 purpose the provision of novel, simple and effective mechanism for controlling the movements of the hydroplanes, both in extending them into operative position, rocking them to the desired angle when maneuvering the boat below the surface of the 20 water, and to fold or ship them when the boat is on the surface of the water.

The invention relates primarily to the 25 type of hydroplanes which are extended and folded by a pivotal movement, and tilted when extended by a rocking movement about a longitudinal axis to present either face thereof to the passing waters to cause the boat to submerge or rise on an even keel.

30 The invention provides tubes or hollow shafts suitably mounted within the boat in transverse relation and adapted to be turned about their longitudinal axes, hydroplanes pivotally connected to the outer ends of the

35 tubes, or hollow shafts, to swing outward into operative position or inward against the sides of the boat into inoperative position; hydroplane-operating mechanism mounted upon the inner ends of the said

40 tubes, or hollow shafts, and connected with the hydroplanes by means passing through the tubes and housed thereby, and tube-operating mechanism for rotating the tubes when the hydroplanes are extended into operative position to present either face of the 45 hydroplanes to the action of the waters to cause the boat to submerge, or to rise on an even keel.

In the accompanying drawings, illustrat-

ing the invention, in the several figures of 50 which like parts are similarly designated:

Figure 1 is a diagrammatic transverse sectional view of a submarine boat embodying my improvement.

Fig. 2 is a longitudinal section drawn on 55 a larger scale through one of the hydroplanes and its operating mechanism, the hydroplane being shown folded.

Fig. 3 is a similar view illustrating the hydroplane in an extended position. 60

Fig. 4 is a sectional plan view drawn on the line 4—4 of Fig. 3.

Fig. 5 is a transverse section drawn on the line 5—5 of Fig. 3.

Fig. 6 is a transverse section drawn on 65 the irregular line 6—6 of Fig. 4.

The numeral 1 designates the superstructure, and 2 the main hull or body of a submarine boat provided with hydroplane operating mechanism embodying the invention. 70 The numeral 3 indicates a supporting plate or deck within the hull.

It is to be understood that the hydroplanes and the operating mechanism therefor are disposed upon opposite sides of the 75 boat so as to maintain the same on an even keel during the various adjustments of the hydroplanes when extending, folding, or tilting them. Inasmuch as the hydroplanes, their mountings, and operating mechanism 80 are alike, a detail description of one will suffice for a clear understanding of the invention.

A tube, or hollow shaft 4, is mounted within the boat in any substantial manner, 85 and at the required position, and is adapted to be turned about its longitudinal axis. The tube, or hollow shaft 4, is arranged to occupy an approximately horizontal and transverse position, and is mounted at or 90 near its ends in suitable bearings 5 and 6 firmly secured to sustaining parts of the boat. While the tube, or shaft 4, is mounted to turn about a longitudinal axis, it is prevented from any longitudinal movement, and any means may be employed for imparting a turning movement thereto. 95

A hydroplane 7 is pivotally connected to

the outer end of the tube, or hollow shaft 4, so as to swing outwardly into operative position, or to fold against the side of the boat into inoperative, or shipped position. As 5 illustrated, a pivot 8 is disposed transversely of the tube 4 and supported at its ends in opposite sides of the tube. The hub portion 9 of the hydroplane is mounted upon the pivot 8 and is formed with oppositely disposed 10 projections 10 to which links 11 and 12 are pivotally connected at their outer ends. When the hydroplane is extended into operative position, or folded against the side of the boat, the opposing sides of 15 the links 11 and 12 touch, as indicated at a (Figs. 2 and 3), thereby forming stop means to hold the hydroplane extended or folded. It is not necessary that the links 11 and 12 touch throughout their length, 20 hence intermediate portions are cut away.

An actuating element 13 is located at the inner end of the tube, or hollow shaft 4, and is mounted to have a pivotal movement imparted thereto. The inner ends of the links 25 11 and 12 are pivotally connected to the element 13 an equal distance from its axis, with the result that the links 11 and 12 remain parallel at every stage of their movement. The element 13 is mounted upon a pivot 14, 30 journaled in arms extending from a casing 30, hereinafter referred to, inclosing the inner end of the said tube 4. The pivots 8 and 14 are parallel and in the same plane

An operating shaft 15 is provided at the 35 inner end of the tube 4, and is supplied at one end with a hand wheel 16 for convenience of operation when it is required to extend or fold the hydroplane. A worm 17 on the shaft is in mesh with worm teeth 40 18 on the actuating element 13. Rotation of the shaft 15 in one direction extends the hydroplane into operative position, and rotation of the shaft 15 in a reverse direction folds the hydroplane against the side of 45 the boat. The links 11 and 12 transmit movement from the actuating element 13 to the hydroplane, and such links passing through the tube 4 are housed and protected thereby.

50 When the hydroplane is extended it is moved to present either face to the passing waters by turning the tube or hollow shaft 4 about its longitudinal axis. This turning of the tube 4 may be effected by any 55 suitable mechanism, and it is observed that such movement is independent of that which extends or folds the hydroplane. In the embodiment illustrated, the inner end of the tube 4 has a segmental worm gear 19 fastened thereto, and such worm gear is in 60 mesh with a worm 20 on a vertical shaft 21, which may be operated in any desired way. The tube, or hollow shaft 4, is turned about its longitudinal axis at such times only 65 when the hydroplane is extended, so as to

tilt such hydroplane to present either face thereof to the passing waters to cause the boat either to submerge or to rise.

Under normal conditions, when the submarine boat is on the surface of the water, 70 the hydroplane 7 is folded against the side thereof. When it is desired to submerge, the operating shaft 15 is actuated, thereby extending the hydroplane into operative position through the link connections 11 and 75 12; the tube 4 is now turned about its longitudinal axis to tilt the hydroplane to present its upper surface to the water, thereby causing the boat to submerge when in motion. When it is desired to rise, the tube 80 4 is turned about its longitudinal axis in a reverse direction, thereby tilting the hydroplane to present its lower face to the passing waters when the boat is in motion, with the result that the boat ascends. When the 85 boat is operating on the surface of the water, the hydroplane is folded against the side thereof by operating the shaft 15 in an opposite direction to that previously practised in extending the hydroplane. 90

To insure operation of the boat on an even keel when submerging or rising, it is essential that the hydroplanes be operated in consonance both when extending them into operative position, folding them into 95 shipped position, or tilting them to present either face to the passing waters to submerge or to rise. This is accomplished by suitable connections between the shafts 21 and the operating shafts 15. As illustrated, 100 the operating shafts 15 are extended at their lower ends, and are provided with bevel gears 22, which mesh with companion bevel gears 23 keyed to the ends of a transverse shaft 24. It will thus be understood 105 that movement of one of the operating shafts 15 will result in a like and corresponding movement of the opposite shaft 15, so that both hydroplanes at opposite sides of the boat are either extended or 110 folded with a like movement.

The shafts 21 may be connected in any preferred manner to cause them and the tubular members 4 to operate in unison, and at an even speed to insure a like movement 115 of the hydroplanes when tilted to cause the boat to submerge or to rise on an even keel. In the embodiment shown, the shafts 21 have bevel gears 25 keyed thereto and in mesh with companion bevel gears 26 secured to the ends of a transverse shaft 27, 120 which, in turn, is geared to a main shaft 28, which may be operated from any suitable source of power, and which is geared to the shaft 27 in any manner to effect rotation thereof.

125 It will be understood from the foregoing, reference being had to the accompanying drawings, that the hydroplanes at opposite sides of the boat are operated alike, and 130

are limited when extended or folded by the link connections between them and their respective actuating means. It is also noted that the mountings are such as to insure firm and substantial supports. It is further observed that the mechanism may be readily installed upon a boat, and is comparatively simple in formation, effective in operation, and adapted to be readily manipulated. The parallel links 11 and 12, besides acting to transmit movement from the actuating elements 13 to the hydroplanes, also serve as stop means to limit the pivotal movements of the hydroplanes in both directions, that is, when lowered into operative position, or folded into shipped position.

In practice, the inner end of the tube, or hollow shaft 4, will be closed by a suitable casing 30 provided with stuffing-boxes through which the operating shaft 15 passes, and suitable stuffing-boxes 31 will also be provided in the bearings 5 and 6 for a like purpose, but as these features are well understood and would readily present themselves to those skilled in the art to which the invention relates, it is not thought necessary to describe or to illustrate them in detail.

While I have shown and described the invention as particularly applicable for the operations of the hydroplanes of a submarine boat, it will be understood that the same construction may be carried out in connection with the operation of the forward and after horizontal rudders of a boat, and that the term "hydroplanes" used in the description and claims is to be considered synonymous with the so-called horizontal rudders.

What I claim is:—

1. In a submarine boat, members mounted within the boat at opposite sides thereof and rotatable about their longitudinal axes, hydroplanes pivoted to the outer ends of said members and rotatable therewith, hydroplane-operating mechanism mounted upon the inner ends of the said members, connecting means between the hydroplanes and the hydroplane-operating mechanism of the respective members and passing therethrough, and adapted to act as stop means to limit the pivotal movements of the hydroplanes in both directions, and means for turning said members about their axes to tilt the hydroplanes when extended to cause the boat to submerge or to rise on an even keel.

2. In a submarine boat, members mounted within the boat at opposite sides thereof and rotatable about their longitudinal axes, hydroplanes pivoted to the outer ends of said members and rotatable therewith, hydroplane-operating mechanism mounted upon the inner ends of the said members, links passing through the respective members and

connecting the hydroplanes with the hydroplane-operating mechanism thereof, and means for turning the said members about their axes to tilt the hydroplanes when extended to cause the boat to submerge or to rise on an even keel.

3. In a submarine boat, members mounted within the boat at opposite sides thereof and rotatable about their longitudinal axes, hydroplanes pivoted to the outer ends of said members and rotatable therewith, hydroplane-operating mechanism mounted upon the inner ends of the said members, parallel links passing through the respective members and connecting the hydroplanes with the hydroplane-operating mechanism thereof, and adapted to limit the pivotal movements of the hydroplanes in both directions by the contacting of the opposing faces of the said links, and means for turning the said members about their axes to tilt the hydroplanes when extended to cause the boat to submerge or to rise on an even keel.

4. In a submarine boat, members mounted within the boat at opposite sides thereof and rotatable about their longitudinal axes, hydroplanes pivoted to the outer ends of said members and rotatable therewith, actuating elements pivotally mounted within the inner ends of the members, connecting means between the hydroplanes and the actuating elements of the respective members and passing therethrough, operating shafts mounted upon the inner ends of the members and geared to the respective actuating elements, and means for turning the said members about their axes to tilt the hydroplanes when extended to cause the boat to submerge or to rise on an even keel.

5. In a submarine boat, members mounted within the boat at opposite sides thereof and rotatable about their longitudinal axes, hydroplanes pivoted to the outer ends of said members and rotatable therewith, actuating elements disposed at the inner ends of the members, parallel links passing through the members and having pivotal connection at their ends with the hydroplanes and actuating elements equidistant from their axes and adapted to limit the pivotal movements of such members in both directions, operating shafts mounted upon the inner ends of the members and geared to the actuating elements, and means for turning said members about their axes to tilt the hydroplanes when extended to cause the boat to submerge or to rise on an even keel.

6. In a submarine boat, tubular members mounted within the boat at opposite sides thereof and rotatable about their longitudinal axes, hydroplanes pivotally connected with the outer ends of the members to turn therewith, gear sectors mounted within the inner ends of the members, parallel links disposed within the members and connecting

the hydroplanes with the gear sectors and serving to limit pivotal movements thereof in both directions, operating shafts mounted upon the inner ends of the tubular members 5 and in gear with the respective sectors, connecting means between the operating shafts to insure simultaneous and like movement thereof, and means for turning the said members about their axes to tilt the hydro-

planes when extended to cause the boat to 10 submerge or to rise on an even keel.

In testimony whereof I have hereunto set my hand this 26th day of March, A. D. 1917.

JOSEPH BARRAJA-FRAUNFELDER.
